(57) CLAIM

The ornamental design for a combined toilet plunger and brush storage container, as shown and described.

DESCRIPTION

FIG. 1 is a perspective view of a combined toilet plunger and brush storage container showing my new design;

FIG. 2 is a front elevation view of FIG. 1;

FIG. 3 is a side elevation view of FIG. 1;

FIG. 4 is a top plan view of FIG. 1 showing the hollow interior;

FIG. 5 is a bottom plan view of FIG. 1; and,

FIG. 6 is a bottom perspective view of FIG. 1.

The broken lines in the figures illustrate portions of the combined toilet plunger and brush storage container that form no part of the claimed design.

1 Claim, 6 Drawing Sheets
